UNITED STATES PATENT OFFICE

DAVID P. GRAHAM, OF DETROIT, MICHIGAN, ASSIGNOR OF ONE-HALF TO LEVI C. HAYDEN, OF TECUMSEH, MICHIGAN.

LOCK FOR MOTOR-VEHICLES.

1,014,145.

Specification of Letters Patent.

Patented Jan. 9, 1912.

Application filed January 9, 1911. Serial No. 601,584.

To all whom it may concern:

Be it known that I, DAVID P. GRAHAM, a citizen of the United States of America, residing at Detroit, in the county of Wayne 5 and State of Michigan, have invented certain new and useful Improvements in Locks for Motor-Vehicles, of which the following is a specification, reference being had therein to the accompanying drawings.

10 This invention relates to improvements in locks for automobiles and other motor vehicles and its object is to adapt the ordinary Yale type of lock to the purpose by connecting to the rotatable barrel of such a lock, means for transmitting motion from 15 said barrel to the part to be operated and providing the barrel with means for yieldingly holding the same from turning to hold the part actuated thereby in the position to 20 which it is turned when the barrel is actuated by its key.

To this end the invention consists in the matters hereinafter more fully set forth, reference being had to the accompanying drawing 25 in which,

Figure 1 is a side elevation of a device embodying the invention, showing the same in operative position; Fig. 2 is a perspective view of the lock detached from its casing; and Fig. 3 shows a modified application 30 of the invention.

For convenience of illustration, the lock is shown as applied to the controlling of the fuel supply to the motor of the vehicle, a 35 suitable valve 1 being provided in the gasoline supply pipe 2 which valve is operated by means of a flexible shaft 3 attached to the stem of the valve and extending upward within a suitable shield or casing 4 secured 40 to the forward side of the dash board 5 or other part of the automobile body adapted to serve as a convenient support therefor. The upper end of the flexible shaft 3 is 45 jointly connected to the inner end of the rotatable bolt 6 of an ordinary lock 7 of the Yale type, by a ferrule 8 secured upon the end of the shaft and formed with a transverse eye to receive a pivot pin 9 passing through holes in ears 10 projecting from 50 the end face of a squared end or head 11 on the inner end of the bolt 6. The lock is 55 inclosed within a suitable casing 12 provided with a flange for securing it to the rear side of the dash in an inclined position, the end flange 13 on the barrel 14 of the lock fitting

within the end of the said casing in the usual manner. At its inner end, the barrel 14 is formed with a projecting lug 15 forming a stop to be engaged by a lug 16 on the end of the bolt 6 and limit the turning of said 60 bolt by its key 17. The barrel is also cast with a ledge 18 at each side forming a place of attachment for a U-shaped spring 19 which is secured thereto by screws with the connecting end portion of the spring lying 65 flat upon one side of the square head 11 of the bolt. When the lock is in place within the casing 12, said casing incloses and protects the spring as well as all of the other parts. The stop 15 limits the turning of the 70 flexible shaft so that it may not be turned farther than necessary to open or close the valve and the spring 19 yieldingly engaging the squared head, holds the bolt turned with the valve in either open or closed position 75 so that it will not be turned by the jar and vibration of the vehicle. By this construction a very neat and compact locking device is secured which may be connected by means of the flexible shaft with any suitable part 80 of the automobile mechanism controlling its use, and the lock located in any convenient place. In Fig. 3, the flexible shaft is shown as supported and guided by a pipe 20 through which it passes, said pipe forming 85 a casing for the shaft.

What I claim is:—

1. A device for the purpose described comprising a lock having a stationary barrel and a rotatable bolt in said barrel having an end extending beyond the barrel and formed with a plurality of faces, a spring secured to the barrel in engagement with one of said faces to yieldingly hold the bolt from turning, a tubular casing inclosing the 90 barrel and spring, and a shaft pivotally attached to the extended end of the bolt at one end.

2. A device for the purpose described comprising a lock having a stationary barrel and a rotatable bolt formed with a squared end projecting beyond the barrel, said bolt and barrel being also formed with projections forming stops to limit the turning of said bolt, a U-shaped spring secured 100 at its ends to the barrel with its connecting middle portion engaging the squared end of the bolt, a tubular casing inclosing the barrel and spring, and a shaft attached to said end of said bolt.

3. A device for the purpose described comprising a lock having a stationary barrel and a rotatable bolt in said barrel having a lug and a squared projecting end, a stop 5 on the barrel to be engaged by the lug, a U-shaped spring secured at its ends to the barrel with its connecting end portion engaging the squared end of the bolt, a tubular casting inclosing said barrel and spring, ears

on the end of said bolt, and a shaft pivotally 10 attached to said ears.

In testimony whereof I affix my signature in presence of two witnesses.

DAVID P. GRAHAM.
